UNITED STATES PATENT OFFICE.

SHULAR BAUM, OF UTICA, NEW YORK, ASSIGNOR TO THE CENTURY CABINET COMPANY, OF UTICA, NEW YORK, A CORPORATION OF NEW YORK.

TALKING-MACHINE.

1,284,988.

Specification of Letters Patent. Patented Nov. 19, 1918.

Application filed October 5, 1917. Serial No. 194,971.

To all whom it may concern:

Be it known that I, SHULAR BAUM, a citizen of the United States, residing in the city of Utica, county of Oneida, and State of 5 New York, have invented certain new and useful Improvements in Talking-Machines, of which the following is a full, clear, and exact specification.

My invention relates to appliances for 10 talking machines and refers particularly to the tone arm and means for allowing the movement thereof.

One object of my invention is a device in which the tone arm has a free vertical and 15 horizontal movement.

Another object of my invention is a device in which the moving parts of the tone arm are subjected to a minimum of frictional wear.

20 Another object of my invention is a device in which the stylus may be removed from, and introduced into, the sound groove of a record with a minimum danger of injuring the undulations therein.

25 Another object of my invention is a device in which the horizontal and vertical movements of the tone arm are limited.

In the operation of talking machines, it is 30 essential that the tone arm carrying the sound box and the stylus have free and unrestricted horizontal and vertical movements in order that the stylus may correctly follow the sound undulations in the sound groove. This can be obtained only by reducing the 35 frictional movement to a minimum and by obviating the inherent weight of this portion of the machine.

As experience has shown that the least injurious effect is produced upon the sound 40 undulations by removing, or inserting, the stylus during the revolution of the record, it is essential that the stylus be removed, or inserted, in such a direction and in such a manner that the point of the stylus will not 45 mar or scratch the undulations at their point of contact with the stylus during this operation.

It is further essential in machines of this 50 character that it be possible to remove the stylus from the sound groove and then swing it away from the record in order to remove or replace the record upon the turn-table, and to maintain the tone arm from descending too far and injuring the stylus and

sound box by the contact of the stylus with 55 some part of the machine.

All of these essentials of a correct and perfect operation of a machine of the character described is accompanied by the device of my invention. 60

In the accompanying drawings illustrating one form of the device of my invention, similar parts are indicated by similar numerals.

Figure 1 is a side plan view of one form 65 of my device, the dotted lines indicating the tone arm in a raised position.

Fig. 2 is a top plan view of Fig. 1, the dotted lines indicating the tone arm in a horizontal revolved position. 70

Fig. 3 is a broken side view of the tone arm, with parts broken away and parts shown in cross-section.

Fig. 4 is a cross-section through the line 4—4 of Fig. 3. 75

Fig. 5 is a cross-section through the line 5—5 of Fig. 3.

Fig. 6 is a cross-section similar to Fig. 5, the tone arm being in the revolved position indicated by the dotted lines in Fig. 2. 80

Fig. 7 is a cross-section through the line 7—7 of Fig. 3.

Fig. 8 is a cross-section through the line 8—8 of Fig. 7.

Fig. 9 is a broken development of the ball cage. 85

The particular form of the device of my invention illustrated in the drawings comprises an annular base 10, fixedly attached to the motor board 11 by means of the screws 90 12, 12. The interior of the base 10 has the annular semi-spherical recess 13, which acts with the annular semi-spherical recess 14 of the revoluble collar 15 as a ball race. The collar 15 is revoluble within the base 10 and 95 is held in revoluble condition therewith by the balls 16, 16, 16 within the ball race. A split flat ring 17 is inserted between the base 10 and the revoluble collar 15 and has within it three equi-distant holes or openings 18, 18, 18, 100 18 large enough for the insertion of the balls 16, 16, 16, so that when the balls 16, 16, 16 are in place within the device they extend through the openings 18, 18, 18 into the ball race formed by the recesses 13 and 14. In 105 this manner the balls 16, 16, 16 have free movement around the ball race and are kept equi-distant from each other by the ring 17,

thus presenting a minimum of friction and preventing the friction which would be incident to their revolution against each other. The tone arm 19 is maintained in pivotal position with the collar 15 by means of the pivots 20, 20 carrying the leather washers 21, 21. A counter-weight spring 22 connects the hook 23 connected to the tone arm 19 with the hook 24 connected with the collar 15. A small flange plate 25, having an indentation 28 at its revoluble extremity to fit into the hole 26 of the base 10, is pivotally attached to the base 10 by means of the screw 27. The hole 28 is sufficiently large to allow of the passage therethrough of a ball 16, and opens into the ball race. The collar 15 is cut away at 29 and carries the inwardly extended lug 30 which acts as a stop for the downward movement of the tone arm 19. The hook 24 acts as a stop for the upward movement of the tone arm 19. The tone arm 19 carries the sound-box 31 which in turn carries the stylus 32 capable of abutment upon the record 33 carried by the turn-table 34.

25 The method of assembling the device is as follows:

The tone arm 19 is pivotally attached to the collar 15 by means of the pivot screws 20, 20. The split ring 17 is then inserted within the base 10 and the collar 15 inserted therein. The collar 15 and the ring 17 are then revolved until one of the holes 18, 18 is opposite the hole 26 and a ball 16 inserted, the collar 15 and the ring 17 are further revolved until the next hole 18 is presented to the hole 26 and a ball 16 inserted, the same operation being repeated for the insertion of the third ball, thus locking the collar 15 to the base 10 by means of the balls 16, 16, 16 within the ball race. The ring 17 is then revolved until the split opening therein and the opening 29 of the collar 15 are opposite the screw 27 which is then screwed in, the ring 17 having been revolved over the opening 29 to prevent the escape of the balls 16, 16, 16. The screw 27 thus projects inwardly and limits the revoluble movement of the collar 15 to the length of the cut away portion 29 and the ring 17 to the length of its split opening.

50 The operation of the device is as follows:—

Assuming that the stylus 32 is upon the record 33 as shown in Figs. 1 and 2 and the turn-table 34 and the record 33 revolving. In order that the stylus may follow the undulations of the sound groove the tone arm 19 is capable of vertical movement by its pivotal movement upon the pivots 20, 20, the weight of the tone arm being counter-balanced by the action of the spring 22. As the pivots 20, 20 are practically in a horizontal plane with the point of the stylus, it is evident that the movement at the pivotal point will be less than if the pivots were placed above such a horizontal plane in order to produce the necessary vertical movement of

the stylus, thus reducing the friction and the wearing away of the moving members, and further that the tone arm is much more evenly balanced by such a construction than when the pivotal point is above the stylus.

70

During the revolution of the record it is essential that the tone arm have a free horizontal movement in order that it may follow the sound grooves, and in my device, as illustrated, this is accomplished by the three-point ball movement of the balls 16, 16, 16 within the ball race, friction being reduced to a minimum by the equi-distant separation of the balls thus obtaining a minimum amount of frictional contact.

80

When it is desired to remove the stylus from the record, the tone arm is raised upwardly, as shown in dotted lines in Fig. 1, until the bottom rearward portion of the tone arm strikes the lower extension of the hook 24 which thus acts as a stop. As the pivotal point of the tone arm is in practically a horizontal plane with the point of the stylus it is evident that the stylus will be removed from the sound undulations in practically a straight vertical direction, thus reducing to a minimum the danger of injuring the undulations in the revolving record. This direct upward removal of the stylus from the record can not be accomplished when the pivotal point of the tone arm is above the stylus, as the arc of movement will not give such a line of removal.

95

When the stylus is removed, the tone arm 19 is revolved into the position shown in the dotted lines of Fig. 2 and allowed to descend, the bottom forward portion of the tone arm striking the lug 30 which thus acts as a stop.

100

I do not limit myself to the particular size, shape, number or arrangement of parts as described and shown all of which may be varied without going beyond the scope of my invention as described and claimed.

105

What I claim is:—

110

1. In a talking machine, in combination, a base, a tone arm carrying a sound box and a stylus, a split collar between the tone arm and the base, said collar being revoluble with the tone arm and within the base, a ball race within the collar and the base, a split ring between the collar and the base, holes within the ring, a ball within each hole of the ring and extending into the ball race, pivotal means connecting the tone arm and the collar allowing a vertical pivotal movement of the tone arm, means for limiting the horizontal movement of the tone arm, means for limiting the vertical movement of the tone arm, and means for inserting the balls into the holes of the ring and the ball race exteriorly of the base.

115

2. In a talking machine, in combination, a base, a tone arm carrying a sound box and a stylus, a split collar between the tone arm

120

125

130

and the base, said collar being revoluble with the tone arm and within the base, a ball race within the collar and the base, a split ring between the collar and the base, holes within 5 the ring, a ball within each hole of the ring and extending into the ball race, pivotal means connecting the tone arm and the collar allowing a vertical pivotal movement of the tone arm, means for limiting the horizontal 10 movement of the tone arm, means for limiting the vertical movement of the tone arm, the means for allowing the movement of the tone arm being in an approximate horizontal plane with the point of the stylus, means for inserting the balls into the holes of the ring 1 and the ball race externally of the base and means for preventing the accidental removal of the balls from the ball race.

Signed at New York in the county of New York and State of New York this 3rd day of 20 October, 1917.

SHULAR BAUM.
